LUBRICATING DEVICE

Harry R. Tear, Evanston, Ill., assignor to The Lubrication Corporation, Chicago, Ill., a corporation of Delaware

Application August 12, 1936, Serial No. 95,499

5 Claims. (Cl. 221—47.4)

This invention relates to lubricating devices and more particularly to factory filled lubricant supply cartridges and to dispensers utilizing such cartridges.

5 Lubricants of various types have, for some time, been marketed in factory filled cartridges and the advantages and desirability of this method of handling lubricants are now too well known to require further discussion. One of the desirable 10 features of cartridged lubricant is that the customer receives assurance that he is actually receiving the brand of lubricant which he desires since the manufacturer's label may be placed on the cartridge at the time it is filled. There 15 might, however, be a tendency on the part of unscrupulous persons to take advantage of the advertising and prestige of other better known manufacturers by obtaining used or empty cartridges bearing the labels of such manufacturers 20 and refilling such cartridges with their own inferior lubricant. This practice would be very unfair to the original manufacturer and also to the customer, since the latter would be deceived into accepting an inferior product.

25 Such unfair practice can be eliminated if the cartridges can be so constructed that refilling after once using is impossible, and it is accordingly one of the objects of the present invention to provide a lubricant cartridge which cannot 30 be refilled.

Another object of the invention is to provide a lubricant cartridge including a piston having an opening therein which is normally closed during original use of the cartridge but which will be 35 opened upon any attempt to move the piston rearwardly, as would be necessary to refill the cartridge.

Another object is to provide a piston for a lubricant cartridge having a normally closed opening which will remain closed against a force in one direction but which will be opened by a force in the other direction.

Still another object is to provide a lubricant dispenser including a feed screw and a cartridge 45 having a movable piston with a normally closed opening in which the feed screw force tends to hold the opening closed but a force in the opposite direction tends to open it.

50 Other objects, advantages and desirable particular constructions will be apparent from the following description when read in connection with the accompanying drawing, in which:

Fig. 1 is a side view of a lubricant dispenser 55 embodying the invention with parts in section.

Fig. 2 is a partial central section similar to Fig. 1 showing a different position;

Fig. 3 is a central section of a modified construction embodying the invention;

Fig. 4 is an enlarged partial view of the construction of Fig. 3; and

Fig. 5 is a view similar to Fig. 3 of a further modified construction.

The dispenser illustrated in Fig. 1 comprises a cylindrical barrel or housing which is closed at one end by a permanently attached cap 2 through which a feed screw 3 extends. The feed screw 3 is preferably connected to the cap by means of a quick release device 4 which may be operated to release the feed screw for free axial movement 10 or which may be threaded connected to the feed screw. A suitable operating handle 5 is secured to the outer end of the feed screw and the inner end thereof carries a cup member 6 for engagement with a cartridge piston.

The opposite end of the barrel 1 is closed by means of a detachable head 7 which carries a lubricant pump formed by a member 8 extending loosely through the head 7 and having an inlet stud 9 and a member 11 slidably mounted on the member 8 and carrying a nozzle 12 of any suitable type. The pump part 8 is rigidly secured to a connector plate 13 which lies inside of the head 7 and which is formed around its periphery with a plurality of notches and cam portions for forming a bayonet joint with a lubricant cartridge.

The barrel 1 is adapted to receive an interchangeable factory filled lubricant cartridge having a cylindrical side wall 14 and a fixed end closure 15 formed with a central outlet opening defined by a spherical wall portion 16 adapted for sealing engagement with the inlet stud 9. The forward end of the cartridge side wall has a plurality of depressed lugs 17 by which the cartridge may be connected rigidly to the connector plate 13. The opposite end of the cartridge is closed by a slidably mounted piston 18 having a central opening therein defined by an outwardly turned flange 19. The opening may be closed by a cap 21 frictionally fitting over the flange 19 and having a reduced portion 22 adapted to fit into the cup member 6.

To operate the dispenser of Fig. 1, the parts are first assembled as indicated and the feed screw 5 may then be turned into the barrel to bring the cup member 6 into engagement with the cap 21. Further turning of the feed screw will create a pressure on the piston 18 forcing lubricant from the cartridge into the pump part 8. Thereafter the nozzle 12 may be placed against

a fitting and a thrust exerted on the handle 5 or barrel 1 in the direction of the nozzle to telescope the pump parts and thereby to eject lubricant from the pump. It will be noted that during 5 operation of the feed screw the thrust exerted thereby tends to force the cap 21 tightly against the piston so that the opening through the flange 19 will be closed and there will be no tendency for the cap 21 to be removed.

10 Fig. 2 illustrates the relative positions of the cartridge parts when the contents thereof have been almost entirely discharged and the piston 18 has moved to a position closely adjacent the end closure 15. It will be appreciated that when 15 the cartridge is completely emptied the piston 18 will lie in contact with the end closure substantially throughout their entire areas so that practically all of the contents of the cartridge will be dispensed. In order to refill the cartridge it 20 would be necessary to force the piston 18 away from the closure 15 to its original position either by inserting a tool through the outlet opening to force the piston back mechanically or by forcing lubricant or other fluid under pressure into the 25 outlet opening. It will be noted from the relative positions of the parts in Fig. 2 that any tool inserted through the outlet opening in the wall 15 would necessarily engage the cap member 21 and a thrust exerted on such tool would cause 30 the cap member to slide off of the flange 19 thereby leaving an uncovered hole in the piston. The cap member 21 would be removed similarly if it were attempted to force the piston back by means of fluid pressure and it will be apparent 35 that with the cap member removed it is substantially impossible to force the piston backwardly in the cartridge. Thus this construction makes refilling of the cartridge a substantial impossibility and insures that the contents of the 40 cartridge are those originally placed therein by the manufacturer.

Figs. 3 and 4 illustrate a modified piston construction which might be substituted for the piston 18 of Figs. 1 and 2 comprising a body portion 24 having a circular periphery adapted to seal against the inner wall of the cylindrical cartridge body and formed at its central portion with an outwardly extending flange 25 connected to a similar flange 26 of reduced diameter. The 45 end of the flange 26 is open to provide a hole through the piston and may be closed by means of a sheet 27 of frangible material such as paper, metal foil or the like which is cemented to the flange 26 as indicated at 28. A cap 29 is formed 50 to fit over the flange 26 and down turned edges of the sheet 27 and has a radial flange 31 to provide a seat for the edges of the cup member 6. The central portion of the cap 29 is substantially flat and overlies the sheet 27 to provide a reinforcement 55 therefor against lubricant pressure in the cartridge. However, if it were attempted to move the piston rearwardly by means of a tool inserted through the cartridge outlet opening or by fluid pressure applied to the cartridge outlet opening, 60 the sheet 27 would be ruptured and the cap 29 would be forced off of the flange 26 thereby substantially destroying the utility of the piston and making it substantially impossible to refill a cartridge successfully.

70 Fig. 5 illustrates a further modified piston construction including a body portion 32 having a central opening defined by an outwardly turned central flange 33, the edges of which are rolled in as indicated at 34 to provide a smooth surface. A sheet of frangible material 35 is cemented 75

over the edge of the flange and a cap member 36 is adapted to fit over the sheet and the flange to reinforce the sheet during normal operation. The cap member is preferably provided with an annular upwardly turned projection 37 of a size 5 to fit within the cup member 6, thereby to assure centering of the cup member 6 on the piston. The piston of Fig. 5 operates in substantially the same manner as those previously described, it being noted that during normal operation the cap 10 36 reinforces the sheet 35 but that any attempt to force the piston rearwardly in a cartridge will result in displacement of the cap 36 and rupturing of the sheet 35.

While several embodiments of the invention 15 have been shown and described, it will be apparent that many changes might be made therein and it is accordingly not intended to be limited to the forms shown or otherwise than by the terms of the appended claims. 20

I claim:

1. A lubricant supply cartridge comprising, a cylindrical wall portion having a fixed closure provided with an outlet opening at one end defined by a flange extending into the cartridge, a 25 piston slidably mounted in the cartridge and forming a movable closure for its opposite end, said piston having an opening therein in register with said outlet opening, and defined by a rearwardly extending circular flange adapted to fit 30 over said first named flange, and a cap frictionally fitting over the outside of said last named flange whereby a force exerted on the cap in the direction of the outlet opening will urge the piston through the cartridge but a force exerted on the 35 cap through the outlet opening will remove the cap from the piston.

2. A lubricant supply cartridge comprising, a cylindrical wall portion having a fixed closure provided with an outlet opening at one end, a piston 40 slidably mounted in the cartridge and forming a movable closure for its opposite end, said piston having an opening therein in register with said outlet opening, a frangible sheet secured over said opening in the piston to close it, and a relatively flat reinforcing member overlying said sheet whereby a thrust on the reinforcing member in the direction of the outlet opening will cause it to reinforce the sheet and to force the piston through the cartridge and a tool inserted 45 through the outlet opening will rupture the sheet and force said member away from the piston. 50

3. A lubricant supply cartridge comprising, a cylindrical wall portion having a fixed closure provided with an outlet opening at one end, a 55 piston slidably mounted in the cartridge and forming a movable closure for its opposite end, said piston having an opening therein in register with said outlet opening, a frangible sheet secured over said opening in the piston to close it, and a cap frictionally secured to the piston and having a relatively flat surface overlying the sheet to reinforce it, said sheet adapted to be ruptured and said cap adapted to be removed by a force exerted thereon through the outlet 60 opening. 65

4. A lubricant supply cartridge comprising, a cylindrical wall portion having a fixed closure provided with an outlet opening at one end, a piston 70 slidably mounted in the cartridge and forming a movable closure for its opposite end, said piston having an opening therein in register with said outlet opening, and defined by a rearwardly extending circular flange, a frangible sheet secured over the edge of said flange to close 75

the opening, and a cap frictionally fitting over said flange and having a relatively flat surface overlying the sheet to reinforce it.

5. In a lubricant cartridge, a piston comprising, a circular body formed around its periphery for sealing engagement with the cartridge side wall, said body having a central opening defined

by an outwardly turned flange, a frangible sheet secured to the edge of the flange and closing the opening, and a cap frictionally fitting over the flange and having a relatively flat surface overlying and reinforcing said sheet. 5
